APPARATUS FOR EFFECTING DISSOLUTION
OR LIXIVIATION

William H. Allen, Eliot Underhill, and Charles F. Ritchie, Trenza, Calif., assignors to American Potash & Chemical Corporation, Trenza, Calif., a corporation of Delaware

Application October 28, 1933, Serial No. 695,644

8 Claims. (Cl. 23—272.1)

This invention relates to an apparatus for effecting the dissolution or lixiviation of solids, and immiscible liquids, and has particular reference to an apparatus for producing solutions of solutes at a definite temperature and having definite concentration of such solutes.

The apparatus of the present invention is of particular value in rapidly producing saturated solutions of a solute, free from any excess or undissolved particles of solute. Heretofore, when it was desired to produce a concentrated solution of a solid, or of a liquid in another liquid in which it is immiscible, particularly a saturated solution free from any particles of undissolved matter, it has been generally necessary to effect the solution in a batch process, in which the solvent is brought to equilibrium with the solute by agitation, after which the contents are permitted to settle before a clear solution can be withdrawn. In prior practice, it has been necessary, if it was desired to produce a saturated solution of a solid in a continuous manner, to use two connected pieces of apparatus, in the first of which the solvent and solute are agitated together continuously to produce a saturated solution. From such apparatus it has been necessary to withdraw a sludge of the saturated solution and undissolved solute to a second apparatus, such as a thickener, to separate the solution from the excess solute, which latter is then returned to the mixing and dissolving apparatus.

It is the primary object of the present invention to provide an apparatus for producing solutions of solutes and especially solids by which a concentrated or saturated solution may be rapidly obtained and from which a clear solution may be withdrawn free from any of the solute while the mixing operations are still being performed in the apparatus.

It is a further object of the present invention to provide an apparatus in which a saturated solution of a solute may be continuously produced and withdrawn from the apparatus free from any undissolved material.

The apparatus of the present invention has been particularly designed for forming saturated solutions of a salt, but it may also be used in the manipulation of sludges or mixtures of solutions and solids for other purposes. For example, the apparatus may be employed in the preparation of concentrated solutions of solids by lixiviation or leaching of salts, ores, or the like. Also, the apparatus may be utilized for the preparation of solutions of liquids in solvents in which the liquids are immiscible. Herein, the description is

given principally by reference to the preparation of solutions of solids.

In the manufacture of many crystalline salts, it is often desired to refine crude salts by recrystallization. This requires dissolution of the crude salt. In many instances, it is also desired to produce a solution having a definite concentration of the constituent. For example, in the production of borax from Searles Lake brine, crude salts containing minor impurities are crystallized from a concentrated solution also containing other salts. These crude salts are refined by dissolving them to form a solution of borax and recrystallizing the pure borax from this solution. In the recrystallization of the borax it is desired to produce single nucleus crystals of good size. The crystallization of borax to produce single nucleus crystals of good size is dependent, among other things, upon controlling the number of crystal seeds present. The control of the number of crystal nuclei present is preferably accomplished by starting with a solution free of solid particles of borax. The apparatus of the present invention enables the production of a concentrated solution of crude salts containing no solid particles, which solution may be utilized for recrystallization of the salt in the desired form of crystals.

In the handling of many solids, it is desired to produce a solution of a definite concentration, which, however, is not saturated at the final temperature at which it is to be used. Such a solution may be prepared in the apparatus of the present invention by first carrying out the dissolution of the solid at a temperature at which the saturation value of the salt in the solvent is equal to the desired concentration. This saturated solution is then rendered unsaturated by changing its temperature to the desired extent. When the solute possesses a solubility which varies directly with the temperature, the desired unsaturated condition is accomplished by heating. When the solubility is an invert one, cooling of the saturated solution is utilized to obtain an unsaturated solution. Consequently, an unsaturated solution may be easily prepared in accordance with the features of our invention, both when the solubility curve increases with increasing temperature and when it decreases therewith.

As applied to the refining of borax, for example, it has been found desirable to effect recrystallization of the borax from a solution containing approximately 16% $Na_2B_4O_7$ at a temperature of about 180° F. In preparing such a solution, the crude borax is dissolved in the ap-

paratus of the present invention at a temperature of about 140° F. to 145° F. At this temperature the saturation concentration is approximately 16% $\text{Na}_2\text{B}_4\text{O}_7$. The saturated solution may then 5 be heated to 180° F. to provide a clear, solids-free solution, containing the desired amount of borax at the desired temperature.

The preparation of controlled concentration solutions in accordance with our invention in-10 volves a regulation of the temperature of the solution during the digestion operation. When the substance being dissolved possesses a low rate of solution, a large heat of solution (i. e. negative heat of crystallization), or both of these prop-15 erties, we have found that careful regulation of the temperature during digestion is often difficult to accomplish. If the solute requires heat for solution, i. e. possesses a negative heat of solution, heat must be supplied in sufficient quantity 20 to both elevate the temperature of the solution to the desired point and to compensate for the heat taken up during the dissolution process. Suitable cooling means are employed when heat is given off during the dissolving process, and in 25 some cases the heat required for elevation of the temperature of the solution may be supplied by the heat given off during the solution process. We provide means for conveniently accomplishing a careful regulation of the temperature of 30 the saturated solution. We thereby obtain solutions having accurately controlled concentrations.

The apparatus of the present invention is de-35 signed to prepare a saturated solution of a solid, which may be continuously withdrawn in a clear state by the provision of a chamber, in one portion of which the solvent and solute undergo agitation together in order to effect rapid solution, while in another portion of the chamber, 40 partially separated therefrom by a suitable division wall or walls, the same body of solutions which has reached substantially the saturation value may become quiescent to permit the continuous withdrawal of a clear saturated solution 45 without the necessity of withdrawing any of the free or undissolved solute. Temperature control in the dissolver tank or container is accomplished by subjecting the mixture of solution and excess solute to a primary heat treatment previous to its introduction into the dissolver and to a secondary heating under careful control in the dissolver. In particular, we found that ease 50 of regulation of the solution temperature is enhanced when the secondary heating is accomplished through the use of steam injected into the solution during the dissolving process. Time lag of control is thereby reduced and balancing of rapid temperature fluctuations is improved.

The present invention, together with various 60 further objects and advantages thereof, will best be understood from reference to a particular form or example of an apparatus embodying the invention. For this purpose, we have hereinafter described a preferred form or example of the apparatus.

In the drawings:

Figure 1 represents a vertical section.

Figure 2 is a section along the line 2—2 of 70 Figure 1.

Figure 3 is a sectional elevation of the impeller employed.

Figure 4 is a plan view of the impeller.

Figure 5 is a vertical sectional view of another 75 form of settler.

Referring to Figures 1 and 2 of the drawings, the apparatus comprises an outer shell 1, preferably of a cylindrical cross-section, having top and bottom closures 2 and 3 which together provide a chamber in which the desired solutions 5 are to be produced. The bottom closure 3 is preferably dish-shaped and provided near its center with inlet pipe 3^a, through which a mixture of solution and undissolved solute may be introduced into the apparatus. Within the apparatus there is provided suitable means for effecting continued agitation, preferably by internal circulation of the sludge in order to effect the desired solution of the solute. Said agitating means preferably include a centrifugal im-10 peller 4 and a vertical circulating well. The circulating well is preferably formed by a cylindrical shell 5 fixed concentrically within the outer shell 1 by suitable means, such as rectifying vanes 6. The rectifying vanes 6 are disposed in the an-15 nular space between the inner and outer shells, preferably four of the vanes being utilized. The vanes are in the form of vertically positioned plates so as to serve the dual purpose of holding the inner shell 5 in position and of reducing 20 swirling or vortex action of the solution during circulation.

The impeller 4 is preferably fixed to a drive-25 shaft 7 journalled in bearings 8 and 9 and supported by the top and bottom plates 2 and 3. 30

The production of saturated solutions in rapid manner is facilitated by the provision of means for securing a positive circulation of the solute and solution in such a manner as to maintain the undissolved solute continuously in suspension 35 in the solution during the dissolving action. In order to best attain this end, the diameter of the inner shell 5 is preferably made such that the cross-sectional area of the well will be about one-half the total cross-sectional area of the outer 40 shell 1. Thus, there is no difference in the velocity of the liquor throughout the circulating path formed by the inner shell 5. In this manner, the apparatus avoids the formation of quiescent areas 45 of liquid in which settling of the solids might occur. The relative areas or diameters of the inner and outer shells, however, may be varied without in some cases greatly affecting the efficiency of the apparatus. The inner shell 5 is made to terminate sufficiently above the bottom 50 plate 3 of the apparatus so as to provide a space for passage of fluid from the well into the an-55 nular space between the shells. The vertical cross-sectional area of this space is preferably substantially equal to the area of the center well provided by the inner shell 5. The cross-sectional area of the circulating path is thereby maintained substantially constant throughout.

The impeller 4 is preferably disposed in this space provided below the inner shell. In its preferred form the impeller is a large volume, slow speed unit capable of imparting substantially stream-line movement to the solution. By "stream-line" movement is meant circulation in which each unit volume of solution or sludge 60 maintains a more or less constant relation in position to every other unit volume of solution or sludge. Thus, swirling is not stream-line movement and is preferably a minimum in the 65 circulation provided. Swirling and vortex action tend to appreciably dissipate the force imparted by the impeller. The impeller 4 is also preferably designed to discharge the liquor substantially entirely in a radial direction. The design 70 75

of the impeller for accomplishing these purposes is best illustrated in Figures 3 and 4.

The impeller comprises impelling vanes 10 mounted vertically upon a base plate 11 at an angle of approximately 45° with diameters passing through the inner edges of the vanes. The vanes 10 are illustrated as short straight pieces, but they may be of convolute contour. The convolute contour, however, is practically straight 10 near the periphery of the impeller, and since the impeller vanes 10 are utilized only at near the periphery of the impeller, the straight and convolute contours are substantially equivalent. The base plate 11 is an annular plate tapered 15 upwardly where it meets the vanes 10 at an angle corresponding to the taper on the bottom plate 3 of the apparatus. For supporting the base plate 11 and impeller vanes 10 on the shaft 7, there is provided a spider 12, having upwardly 20 and inwardly extending braces 13, connecting at one end with the base plate 11 and at their other end with a hub 14 for the impeller which is keyed to the shaft 7. In order to prevent undue liquor slippage through the impeller, an 25 annular cover plate 15 is mounted on the tops of the vanes 10. This top plate is preferably formed at a taper parallel to that of the bottom plate 11.

The diameter of the impeller 4 is preferably 30 equivalent to that of the well 5 in order to facilitate the maintenance of "stream-line" movement throughout the system. For the same reason, the height of the vanes 10 is such that the area defined by the outer edges of the plates 11 and 35 15 is equivalent to the cross-sectional area of the center well provided by the inner shell 5. In this way, the cross-sectional area of the circulating path through the impeller and around the well may be made substantially constant.

40 The mixture of solution and undissolved solute introduced through the inlet 3^a circulates directly through the impeller and into the circulating body of the solution. Thorough mixing of the fresh ingredients with the solution and solute 45 in the dissolver is thereby accomplished. Also, by spacing the annulus 11 only a short distance from the bottom 3, a stream of solution is continuously by-passed from the main circulation stream at the edge of the impeller into the space 50 beneath the impeller and back into the main stream. The likelihood of deposition of undissolved solute in the dead space below the impeller is thereby decreased.

55 The rate of upward flow created by the impeller should preferably be sufficient to prevent packing of settled particles in any part of the system and to maintain all particles in suspension in the solution. In some cases it may be desirable to employ a rate of flow substantially 60 equal to or even greater than the settling rate of the largest particles in suspension in the solution. We have found that under certain conditions and particularly when dense sludges are 65 present a rate less than the settling rate of the largest suspended particles can be employed.

The apparatus is also provided with means for 70 baffling off a portion of the mixture of solution and suspended solute from the main body thereof undergoing agitation or circulation. This baffling means permits solution which has reached the desired concentration to become quiescent so that suspended undissolved solute may settle therefrom. This may be accomplished by the provision 75 of a cone 16 disposed above the inner shell

5 and within the outer shell 1. This conical shell operates as a baffle preventing the communication of the turbulence due to agitation to the saturated solution undergoing settling in the top of the shell 1. The diameter of the 5 conical shell 16 may be either larger or smaller than that of the main portion of the shell 1. Herein it is shown as slightly smaller than the inner diameter of the outer shell 1, so that liquid within the outer shell flows over the upper edge 10 of the cone. It is supported concentrically within the inner shell 1 by suitable means, such as the straps 17. At its lower end it is preferably braced from the inner shell 5 by braces 18. The main body of the settler or baffle cone 16 preferably has a slope somewhat greater than the angle of repose of the settled particles. At the bottom the cone is provided with an outlet connecting with the short nipple 19, which nipple 19 is of greater diameter than that of the shaft 7. The 20 shaft 7 is preferably provided with a helical screw section 20 where the shaft extends through the nipple 19. The mechanism for operating the shaft 7 with the screw section 20 and the impeller 4 may be any suitable drive means, not 25 shown, preferably connected to the upper end of the shaft. The rotating helical screw section 20 is preferably of large pitch and of a diameter sufficient to provide a close fit in the nipple 19. It serves to forcibly eject any solids which may 30 settle in the conical settler 16 into the circulating zone existing therebelow.

The apparatus also preferably comprises suitable means, such as the outlet pipe 21, for withdrawing the liquor from a point near the axis 35 of the apparatus, and preferably slightly above the cone 16. This is directly opposed to the conventional settler operation in which the mixture of solids and liquids is introduced near the middle at the top and the clarified solution with- 40 drawn as an overflow at the periphery. Two zones of localized disturbance exist in a settler, one at the inlet area and the other at the outlet area. In the conventional settler, the location of the inlet at an axial point at the top creates 45 an area of great localized disturbance and turbulence in the center of the settler. Settling is therefore diminished until the liquor flows beyond this area of localized disturbance. In the apparatus of the present invention the intensity 50 of the disturbance caused by the introduction of the liquor or suspension of solids in liquor into the settling cone is greatly minimized by distributing the incoming liquor around the periphery of the settler. Settling then occurs 55 quickly and the settled solids soon come in contact with the walls of the settler and pass down to the outlet orifice 19. By so introducing the suspension of undissolved solids at the periphery 60 of the settler and locating the outlet conduit near the middle and the top thereof, we are enabled to continuously draw off saturated solution which is substantially free of suspended solute.

In the operation of the apparatus, the solution 65 and excess undissolved solute are continuously introduced through the inlet 3^a. The impeller 4 is continuously operated to effect circulation of the solids and solution around the inner shell 5, and the clear saturated solution is continuously withdrawn through the outlet 21. In operation, the apparatus may, if desired, be operated entirely full of liquid. The circulation of solute and solution over the top of the internal shell 5 75

draws most of the suspended solids down through the shell, and only a small portion of undissolved solute overflows the edges of the baffle and settling cone 16. This small portion will settle out 5 of the liquor within the settling cone 16, if the dimensions of the unit are correct for the particular materials treated.

The rate of removal of the solution and its temperature are so controlled that the liquor is 10 retained in contact with suspended solute until saturation or substantial saturation of the solution with respect to the solute is reached. The control of the temperature of the solution being prepared involves two major factors. Sufficient 15 heat must be supplied or withdrawn to counter-balance the heat of solution of the solute in the solvent and to raise or lower the temperature to the desired point for producing the saturated solution. When the solubility increases directly 20 with temperature, heat will be taken up during solution and also a high temperature must be used for the production of a concentrated solution. Thus for this class of salts, considerable heat will be required during the process. If the 25 solute possesses an invert solubility curve, heat will be given off during the solution process and more concentrated solutions will exist at the lower temperature. Consequently cooling or refrigeration will be required for the dissolution of 30 such solutes.

A careful control of the temperature in the dissolver is often difficult to accomplish. This is particularly true when the solute is slow to dissolve and when a large heat of solution is involved. Borax, for example, possesses a comparatively slow rate of solution and a heat of solution of approximately 26,000 calories per 35 gram-mol. We have found that the heat required for maintenance of a uniform temperature 40 within the dissolver will vary considerably.

In accordance with another feature of this invention, we accomplish the heating in two steps. We have found that a close control of the final temperature is facilitated by effecting a 45 portion of the total heating required in a primary operation and the remainder in a secondary heating within the dissolver. The distribution of the heating between the primary and secondary treatments will vary with various materials 50 being dissolved. The heating required in the dissolver is desirably accomplished by injecting stream under close control. We have found that close control is particularly well accomplished 55 when this secondary heating is by means of steam injected under control into the solution in the dissolver. We supply steam nozzles or injectors 22 which inject steam preferably into the path of liquid in the annular space between the two shells 1 and 5 of the apparatus. The 60 mechanism for controlling the amount of steam introduced may be any suitable accurate thermostatic control device operating against the solution in the dissolver or in the outlet conduit.

The heating accomplished by steam may if 65 desired be provided by the use of an external heater in parallel with the dissolver. A portion of the solution is then continuously withdrawn, passed through the heater and returned to the dissolver. When using an external heater in 70 parallel with the dissolver for temperature control purposes, the circulation effected through the withdrawal of solution and solute and its return may conveniently replace the combination of internal well and centrifugal impeller de-

scribed herein. That is, an outside pump transferring solution and solute from the dissolver through the heater and returning it to the dissolver can be used to serve as a circulating means. Thermostatic control of the heating to be employed or effected in an external heater is also desirable, but close control is often more difficult to effect than with heating by steam injection.

The production of a clear liquor is dependent 10 upon the settling area provided in the settler 18 and to some extent upon the presence of a zone of quiescence in the tank and just below the rim of the settler. The amount of settling 15 which will result in any given settling zone is dependent among other factors, upon the degree of quiescence or conversely upon the presence or absence of influences which tend to cause turbulence or liquor disturbance in the settling area. In the present instance, the settler 20 is preferably located sufficiently above the circulation well that the greater part of the velocity head present in the circulation path is dissipated before the solution reaches the inlet rim of the settler. The actual settling area 25 formed by the settler per se is then located in an area removed from the disturbing influence of the circulation effected in the lower part of the dissolver. Some additional settling may be accomplished by increasing the distance between 30 the settler rim and the top of the circulation well to thereby increase the extent of the quiescent area.

The creation of this quiescent area between 35 the circulation well and the rim of the settler 35 may be enhanced by the use of suitable baffle plates 30 preferably stream-lined to possess a concave surface on their lower faces and attached to the inner surface of the dissolver shell 1. These baffles will be preferably so disposed 40 as to divert the upward direction of flow of the liquor in the circulation path toward the interior of the circulation well. The velocity head of the liquor moving toward the rim of the settler 45 is then appreciably reduced and the production of the desired quiescent area enhanced.

In accordance with another feature of our invention we also provide another form of settler which provides greater settling area. Referring to Figure 5 of the drawings there is shown a 50 duplicate dissolver unit of that shown in Figure 1, the same numerals referring to like parts in both figures. In this Figure 5, the settler 16 of Figure 1 is supplemented by an additional 55 superimposed cone settling unit 26. It may be of similar design to the cone 16 and its settling area may have any desired relation in size to that of the lower cone 16. Herein, we have shown the conical units 16 and 26 as being 60 equivalent in design and size. In the operation 65 of this unit the liquor level is carried at or above the rim of the top settler 26 and will be determined by the location of the outlet conduit 27. The mixture of solution and undissolved 70 solute above the top of the inner shell 5, first fills the settler 16, and then fills the settler 26. Clear liquor is drawn off simultaneously through outlets 28 and 27. The rate of combined withdrawal will determine the duration of the retention period for any particular piece of equipment. The relative rates of withdrawal through the two outlets are preferably regulated so that the volumes withdrawn will be in direct proportion to the settling capacities (i. e. capacities for 75

producing clear liquor) of the units 16 and 26. With an apparatus similar to that described herein, it will usually be desirable to control the withdrawal of clarified liquor so that it is divided substantially equally between the conduits 21 and 27. This control may be accomplished in any suitable manner, as by valves or by using conduits of predetermined cross-section which will permit passage of only the desired flow.

Undissolved solute which settles in the lower unit 16 is passed, as in Figure 1, into the circulating stream near the top of the well 7. Solute removed from the upper cone 26 is preferably returned to the circulating stream in some manner which will not disturb the liquor in the lower cone. We accomplish this by providing a restricted section 28 from the bottom of the cone 26 to a point in the lower cone 16, but below the zone of quiescence within which clear liquor is produced. In this manner we produce clear liquor in each settler and return all the excess solute to the circulating stream at the top of the circulation well 5. When particles settling in the upper cone are passed into the lower cone, the outlet orifice 19 of the latter is made large enough to permit the continuous withdrawal of all the settled particles.

Movement of the excess or settled solute through the several settler orifices 19 and 33 is expedited by the use of a helical screw 29 similar to that described for Figure 1. By locating the helical screw 29 around the impeller shaft 9 from a point below the lower settler to above the orifice of the upper settler, continued movement of solids through both settlers is conveniently expedited. The use of such a screw section also improves movement through the leg 28.

When using a multiple cone settler, as shown in Figure 5, the lower settler is preferably arranged sufficiently above the well 5 to provide a quiescent zone in which dissipation of the velocity head of the upward moving liquor takes place. Baffle plates 30, as previously described, may be employed if desired to assist the dissipation of this velocity head.

To assist in the maintenance of the quiescent zone within the lower settler 16 and to prevent turbulence therein as a result of settling particles in the liquor between the two settlers, we provide a skirt 31 which extends from the rim of the upper settler 26 to a level close to the rim of the lower settler. The distance between the lower edge of the skirt 31 and the rim of the lower settler is made sufficient to permit entrance of that volume of liquor which it is desired to settle in the lower settler. Suitable vents as shown at 32 are provided near the juncture of the skirt with the upper settler to permit the escape of air present between the upper settler and the skirt when the apparatus is filled.

While we have described our invention by reference to the preparation of solutions having definite concentrations of dissolved constituents, it should be obvious that it is also applicable in many instances where the dissolution of solids in a solvent is encountered. For example, lixiviation processes and leaching processes may be carried out in the present apparatus either where a particular concentration of solution is desired or not. It is also obvious that in case of a leaching or lixiviation process provision may be made for withdrawal of solids. The use of our apparatus in multiple units with solids and liquors passing concurrently may also be desirable in leaching

or lixiviation processes. It is also apparent that the solute and solvent may be separately introduced in the apparatus in place of being introduced through the common inlet 3a.

While the particular form of the apparatus here described is well adapted to carry out the objects of this invention, it is to be understood that various modifications and changes may be made without departing from the principles thereof, and that this invention includes all such modifications and changes as come within the scope of the appended claims.

We claim:

1. An apparatus for dissolution or lixiviation, comprising means for forming a dissolving chamber for solute and solvent having an inlet and an outlet, means for dividing the lower portion of said chamber into concentric portions of substantially equal cross-sectional area through which solvent and solute may be circulated, a centrifugal impeller for circulating solvent and solute therethrough, an inverted conical baffle plate providing a settling zone in the upper portion of said chamber into which solution may overflow and having a discharge orifice for the return of settled particles to the lower portion of said chamber, and means for forcibly passing particles through said discharge orifice.

2. An apparatus for preparing solutions, comprising means for forming a chamber for holding solute and solvent, a circulating well dividing the lower portion of said chamber into up and down circulation paths of substantially equal cross-sectional area, a centrifugal impeller rotatably mounted in said chamber to effect circulation of solute and solvent through said path, means for forming a settling zone in the upper portion of said chamber into which solution and solute may overflow from said circulation path, means for withdrawing a clarified solution from said settling zone, and means for returning solute from said settling zone to said circulation paths.

3. An apparatus for dissolution or lixiviation, comprising means for forming a chamber for holding solute and solution, an inverted conical-shaped baffle plate dividing said chamber into an upper settling zone and a lower agitating zone, said baffle plate being disposed to permit influx of solution around its upper periphery and having a lower discharge orifice, the agitating zone of said chamber being provided with means for dividing the same into concentric up and down circulating paths, an impeller for circulating solvent and solute down the central path and up the annular return path, the shaft for said impeller being provided with means for forcibly ejecting settled particles through the orifice of said baffle plate.

4. An apparatus for dissolution or lixiviation, comprising means forming a chamber for holding a solute and solvent, a downwardly contracting baffle means in said chamber for dividing the same into an upper settling zone and a lower zone for agitation of solvent and solute, said baffle means permitting an influx of solute at its upper periphery and its lower end being opened for the return of settled particles to the agitating zone, an inlet into the agitating zone, an outlet for solution near the upper central portion of the settling zone formed by said baffle plate, a baffle in said agitating zone dividing the same into up and down circulating paths, and means for forcing the solute and solvent to pass through said circulating paths, the lower end of the first-men-

tioned baffle being not substantially lower than the upper end of said second-mentioned baffle.

5. An apparatus for effecting dissolution or lixiviation, comprising means for forming a dissolving chamber, a downwardly contracting baffle in the upper portion of said chamber for forming a settling zone, a baffle in the lower portion of the chamber for forming a circulating agitating zone, the first-mentioned baffle permitting an 10 influx of solute at its upper periphery at a point spaced substantially from the circulating path of solute and solvent in the lower portion of said chamber, said baffle at its lower end being opened for return of settled particles to the agitating 15 zone, an inlet into the agitating zone, and an outlet for solution near the upper portion of the settling zone formed by said first-mentioned baffle.

6. An apparatus for effecting dissolution or lixiviation, comprising means for forming a dissolving chamber, a downwardly contracting baffle in the upper portion of said chamber for forming a settling zone, a baffle in the lower portion of the chamber for forming a circulating agitating zone, the first-mentioned baffle permitting an 20 influx of solute at its upper periphery at a point spaced substantially from the circulating path of solute and solvent in the lower portion of said chamber, said baffle at its lower end being opened for return of settled particles to the agitating 25 zone, an inlet into the agitating zone, an outlet for solution near the upper central portion of the settling zone formed by said first-mentioned baffle, and an impeller for forcing solute 30 and solvent to circulate through said circulating path.

7. An apparatus for effecting dissolution of lixiviation, comprising means for forming a dissolving chamber, a downwardly contracting baffle in the upper portion of said chamber for forming a settling zone, a baffle in the lower portion of the 5 chamber for forming a circulating agitating zone, the first-mentioned baffle permitting an influx of solute at its upper periphery at a point spaced substantially from the circulating path of solute and solvent in the lower portion of said chamber, 10 said baffle at its lower end being opened for return of settled particles to the agitating zone, an inlet into the agitating zone, an outlet for solution near the upper portion of the settling zone formed by said first-mentioned baffle, and means for forcing 15 settled particles through the open end of said first-mentioned baffle into the lower portion of said chamber.

8. An apparatus for effecting dissolution or lixiviation comprising means forming a dissolving 20 chamber, means for forming a circulation well in the lower portion of said chamber to divide said chamber into a circulation path, an inlet to the lower portion of said chamber, an impeller for causing solute and solvent to move down the interior of said well and up the outside thereof, 25 baffle means for forming a settling zone in the upper portion of said chamber into which zone solution may flow from said agitating zone and from which settled particles may be removed, and a 30 liquor outlet for said settling zone.
